DARK-FIELD CONDENSER FOR
MICROSCOPESRudolf Straubel, Jena, Germany, assignor to firm
Carl Zeiss, Jena, GermanyApplication February 20, 1932, Serial No. 594,347
In Germany March 10, 1931

3 Claims. (Cl. 88—40)

The invention concerns a dark-field condenser for microscopes, having only one reflecting surface, which distinguishes over the known condensers of this kind by a specially simple form

5 and therefore can be manufactured at a comparatively low cost. The invention consists in that the reflecting surface of the condenser has approximately the form of an ellipsoid of revolution in the foci of which are placed the light source and the object, respectively. A corresponding toric or spherical form may be substituted for the said ellipsoidal one.

With respect to the fusion of the rays, condensers of the said kind are required to have the 15 light source, when in use, always assume one and the same position relatively to the reflecting surface. This condition is arrived at in the most simple manner by rigidly connecting the light source and the condenser. Further, the 20 condenser may be improved by providing a variable diaphragm for restricting the aperture of the pencil of illumination rays, this diaphragm suitably being a tube which envelops the light source and is displaceable in the direction of 25 the axis of revolution of the ellipsoid.

The accompanying drawing represents in elevation, in a central cross section, a constructional example of the condenser according to the invention.

30 In the said example, a housing *a* encloses a glass block *b*. This glass block *b* has a silvered exterior surface *c* which represents part of an ellipsoid, and a semispherical recess *d* the spherical centre of which coincides with one focus of the reflecting surface *c*. Part of the surface of the recess *d* is provided with a non-transparent layer *e*. To the housing *a* is connected a cylindrical part *f* in which a tubular diaphragm *g* can be displaced by means of a lever *h* guided 35 by a helical slot *i* in the direction of the axis of revolution of the exterior surface *c*. The part *f* is surrounded by another cylindrical part *k* which also has a guide slot *l* for the lever *h*. Both cylindrical parts *f*, *k* are closed by a lid *m* which in 40 its turn is provided with a cylindrical part *n* receiving the holder *o* for an incandescent lamp

p. In order to avoid the incandescent filament being sharply imaged in the preparation to be examined, the bulb of this lamp *p* is slightly frosted.

When using the condenser, the lamp-holder *o* is clamped in the part *n* by means of a screw *q* in such a manner that the incandescent filament of the lamp *p* comes to lie in the spherical centre of the recess *d*. When in this position, the incandescent lamp *p* is enveloped by the tubular diaphragm *g*. By shifting the lever *h* in the guide slot *l*, the aperture of the pencil of illumination rays is reduced by the diaphragm *g* until all rays are stopped down completely. The condenser is placed with its lid *m* on the stage of the microscope, the cylindrical part *n* projecting in the usual manner into the illumination aperture which is provided in any microscope stage. The object slide with the preparation to be examined is placed on the upper surface of the glass block *b*.

I claim:

1. A dark-field condenser for microscopes, having only one reflecting surface, this reflecting surface having the form of an ellipsoid of revolution, the condenser being adapted to receive in one focus of the reflecting surface the object to be illuminated so that light is concentrated on this object when emanating from the other focus.

2. A dark-field condenser for microscopes, having only one reflecting surface, this reflecting surface having the form of an ellipsoid of revolution, the condenser being adapted to receive in one focus of the reflecting surface the object to be illuminated, and a light source fixed to the condenser, this light source lying in the other focus of the reflecting surface.

3. In a dark-field condenser according to claim 1, a tubular diaphragm attached to the condenser, the axis of the said tubular diaphragm being parallel to the axis of the condenser, the said tubular diaphragm being displaceable in the direction of the said axes and going round the said other focus of the reflecting surface.

RUDOLF STRAUBEL.
